OIL WELL PUMP VALVE

Grafton M. Stewart, Stamford, Conn.

Application May 25, 1949, Serial No. 95,196

1 Claim. (Cl. 251—147)

1

The invention here disclosed relates to the construction of valves such as used in oil well pumps.

Special objects of the invention are to provide a valve construction which will maintain its effectiveness over long continued pumping operations and which in effect will be self-servicing in maintaining a proper seal in spite of foreign matter in the oil and such wear as may be caused by constant operation of the valve.

Further special objects of the invention are to provide a valve having such attributes which will be made up of few, simple, rugged parts and which can be produced at low cost.

Other desirable objects attained by the invention and the novel features of construction, combination and relation of parts through which the purposes of the invention are accomplished, are set forth and will appear in the course of the following specification.

The drawing accompanying and forming part of the specification illustrates a present commercial embodiment of the invention. Structure, however, may be modified and changed as regards the immediate illustration, all within the true intent and broad scope of the invention as hereinafter defined and claimed.

Fig. 1 in the drawing is a front elevation of the new valve construction, partly broken away and showing the drop at the top of its stroke in the valve cage;

Fig. 2 is a substantially central vertical sectional view of the same showing the drop seated and sealed at the bottom of its stroke in the valve cage;

Fig. 3 is a top plan view of the valve cage;

Figs. 4 and 5 are horizontal sectional views as on substantially the plane and in the direction of the arrows of line 4—4, 5—5, Fig. 1.

The valve in Figs. 1 and 2 is shown as the upper or traveling valve but, as will appear, the invention may be incorporated, as well, in the lower or standing valve and in other special valve constructions.

The important features of the invention are the construction of the drop with an upper, piston element 7, a lower, conical valve element 8 and an intermediate, compressible, expandable valve disc 9 and the provision of the cage 10 with a composite valve seat member 11 having a conical valve seat 12 at the bottom for the conical valve element 8, and above that an annular cylindrical valve seat 13 for the sealing disc 9.

The valve discs 8 and 9 are shown loosely held to the piston 7 by a stud 14 which may be formed

2

integrally with the piston and which is shown as riveted or headed over at the lower end at 15 to loosely secure the parts together.

The upper, piston member 7 is shown as cylindrical in form to guide smoothly and easily in the cage and is heavy enough to give the drop a desirable weight.

All three elements of the drop, that is, the piston 7, compressible-expansible sealing disc 9 and conical valve disc 8, are of a size to slide freely and easily in the valve cage. The sealing disc is of an elastic material such as a synthetic rubber or plastic which is uninjured by oil or other products being pumped, and while small enough in normal, uncompressed state to slide freely in the cage, it is expandable under the weight of the piston and the hydrostatic head thereon sufficiently to make sealing engagement with the surrounding annular valve wall 13 when the lower valve element 8 is on valve seat 12.

The valve cage is shown as having long, wide ports 16 in the sides of the same, providing maximum, unimpeded flow through the valve.

The combination conical and cylindrical valve seat ring 11 is shown secured up against a stop shoulder 17 in the lower end of the valve cage by a screw member 18 which may be the upper end of the next pull-rod connection, coupling or other member ordinarily screwed into the bottom of such valve cage.

Because of the expandable, self-adjusting character of the sealing disc, the annular valve seat 13 needs only to be machine finished by ordinary methods. The conical valve seat 12 will be kept clean by normal flow of the pumping liquid. Further to assure good sealing engagement of the metallic valve element 8 with this seat, the drop may have rotary motion imparted thereto by forming the lower portion of the conical valve element 8 with flutes 19 inclined to enable the liquid to impart twisting moments to this element and the drop upon movement of the drop in opposite directions. These rotary impulses cause the valve to apply a scouring and cleaning engagement between the conical valve faces.

As a result the drop operates to keep the conical valve faces clean and closely sealing. The expandable disc, on the other hand, seals off the valve in case there is any occasion for slight leakage between the metal-to-metal engaging parts.

The combination valve ring 11 is readily removable and replaceable in the lower end of the valve cage.

The operating parts are few in number and of simple, rugged and low cost construction.

What is claimed is:

A valve for oil well pumps comprising a vertically extended valve cage having a conical valve seat at the bottom of the same and a cylindrical wall extending upwardly from said conical valve seat, a drop confined in said valve cage and freely slideable vertically in said cylindrical wall portion of the cage, said drop comprising an upper cylindrical piston element, a lower conical valve member, an expansible valve disc between said piston element and valve member, said piston element, valve member and expansible valve disc being all of substantially the same peripheral dimensions, enabling said valve drop to be guided and to slide freely in said cylindrical portion of the valve cage and a stud carried by said upper piston element, projecting loosely down through said expansible valve disc and said conical valve member and having a confining head spaced below said valve member and loosely con-

fining said member and valve disc to said piston element whereby the liquid being pumped may pass between said loosely connected parts of the drop to keep the expansible valve disc free for expansion and contraction to seal against the surrounding cylindrical wall.
